SAFETY RAZOR CASE

Meyer J. Shnitzler, Brookline, Mass., assignor to Gillette Safety Razor Company, Boston, Mass.,
a corporation of Delaware

Application May 3, 1949, Serial No. 2,419

Term of patent 14 years

(Cl. D58—12.6)

To all whom it may concern:

Be it known that I, Meyer J. Shnitzler, a citizen of the United States, residing at 17 Greenough Circle, Brookline, Massachusetts, have invented a new, original, and ornamental Design for Safety Razor Cases, of which the following is a specification, reference being had to the accompanying drawings, forming a part thereof, in which:

Fig. 1 is a view in perspective of a safety razor case in closed condition showing my new design; and

Fig. 2 is a corresponding view of the case in open condition.

I claim:

The ornamental design for a safety razor case, as shown.

MEYER J. SHNITZLER,
